No. 857,253.

PATENTED JUNE 18, 1907.

J. L. McMILLAN.
LOOSE LEAF BINDER.
APPLICATION FILED APR. 20, 1906.

UNITED STATES PATENT OFFICE.

JOHN L. McMILLAN, OF SYRACUSE, NEW YORK.

LOOSE-LEAF BINDER.

No. 857,253.

Specification of Letters Patent.

Patented June 18, 1907.

Application filed April 20, 1906. Serial No. 312,810.

To all whom it may concern:

Be it known that I, JOHN L. McMILLAN, a citizen of the United States, residing at Syracuse, in the county of Onondaga and State of New York, have invented certain new and useful Improvements in Loose-Leaf Binders, of which the following is a specification.

This invention pertains to "loose-leaf binders," and consists in a novel construction whereby the user is enabled to hold the binder in one hand and manipulate the impaling hooks or divided rings with the other hand, removing, replacing or rearranging the leaves as desired, without the necessity of laying the binder upon a table or support as is commonly required.

The construction is illustrated in the accompanying drawings, wherein—

Figure 1 is a perspective view of the improved binder, portions of the lids or cover-boards being broken away; Figs. 2 and 3 transverse sectional views through the mechanism of the binder, respectively showing the impaling hooks or rings closed and open; Fig. 4, a longitudinal sectional view through the lower end of the binder mechanism; Fig. 5, a perspective view of the actuating rod or rock-shaft and its stop, detached and removed from the binder; Fig. 6, a perspective view of the cap or cover-plate; Figs. 7 and 8, detail views of the inner ends of the impaling hooks or divided-ring members, showing how the actuating rock-shaft is mounted therein.

As heretofore commonly constructed, binders of this class have required the use of both hands to open and close the impaling hooks or rings, the binder being laid upon a table or support to permit the two hands to be so used. It frequently happens, however, that the person using the binder, has occasion to remove or to insert a leaf or leaves while holding the binder in his hand, and often where there is no convenient table or like support. The present invention meets this want, affording a ready means of opening and closing the impaling hooks or rings by one hand, and leaving the other free to support the binder, while this is being done.

The binder comprises a trough-shaped member A, which serves as a support for the impaling hooks or divided rings B, of which there may be any desired number, according to the dimensions of the binder; a bent or cranked actuating rod C, which serves also to

connect proximate inner ends of the ring sections or members; a concave backing or stiffening member D, which serves also as a stop to limit the opening of the impaling hooks or rings; a cover-plate H to conceal the mechanism; and the usual back and cover-boards E, F, and G.

The ring-support A has its longitudinal edges curled over or fashioned into tubular barrels a, a, to receive and hold pivot wires or rods b, b, on which are strung or pivoted the half rings or members c, d of the impaling hooks or rings B. The support A is made of sheet metal or other suitable material. The barrels a, a, are cut away at those points at which the hooks or ring members B, B are located, said members being held by the walls of these openings from shifting laterally. Similarly, the cover-plate or cap H is notched, coincidently with the barrels a, and for a like purpose, the cover being of slightly arching cross-section, with inturned edges to fit over and clasp the barrels a, a, as shown in Figs. 2 and 3.

The backing or stiffening member D is secured to the back E in any convenient way, the ring-support A being first attached to said backing, preferably by eyelets or rivets h, though other means of attachment may be adopted if desired. Before assembling these parts, the actuating rod C is applied to the impaling hooks or divided rings B, the inner ends of which are cut away one-half their thickness so as to lap past each other while the two members lie in the same plane, and these overlapping ends are provided with elongated notches d' to receive rod C.

The actuating rod is merely a wire of suitable stiffness, having cranked portions e, between the divided rings or pairs of impaling hooks, another cranked portion f, and a laterally-bent end portion g, preferably provided with a knob or handle, by which to rock or oscillate the rod. The cranked portions e and f are at an angle to each other, that is to say, the portions e extend radially from the main body of the rod, at one angle, and the portion f at a different angle, so that while the portions e find a bearing against the under face of the cap or cover-plate H, the portion f bears against the ring-support A, when the rings are opened or separated, as best illustrated in Fig. 3.

By turning the rod C to the right, that is, in the direction of travel of the hands of a clock, by means of the handle portion g,

those portions of the rod which are seated or journaled in the notches d' of the rings or impaling hooks acting as pivots or journals for the rod, the cranked portion f will be caused to swing upward and to the left with reference to the vertical plane of the axis of the journal portions of said rod, as seen in Fig. 3,—that is to say, it will swing to a point progressively farther to the left of said plane as it rises toward and approaches a horizontal position, until it finally clears or ceases to bear upon the bottom of support A, as indicated in Fig. 2. The cranked portions e will at the same time and by reason of said rotation of the rod about its journal portions seated in the notches d' , swing upward and toward the right.

Owing to the length of the crank portions e and the comparatively flat arch of cover-plate H, said crank portions e will cause the pivots or journals resting in the notches d' to descend, and to carry down with them the inner or short arms of the impaling hooks or ring members, thereby throwing together the upper or outer ends of said hooks or members and closing them. The rotation of the rod C is continued until the crank-arms e pass slightly beyond the middle of the arch of the cover-plate H, against which they bear with some force by reason of the natural outward pressure of the leaves tending to open the rings and to lift the pivots and the rod C.

To prevent the crank-arms e from passing materially beyond such middle or locking point, a stop i is provided, which may conveniently be a strip or block of wood fitted within the supporting member A, notched to receive one of its inturned edges, and retained in position by the cover-plate H and by two rings, between which it lies, as seen in Fig. 1. The stop-block is shown detached in Fig. 5, and in position in Fig. 3.

When the rod C is rotated in the reverse direction or backward with reference to the travel of the hands of a clock, the cranked portion f bearing upon the support A causes the journal portions of the rod, or those portions seated in the notches of the ring members, to rise, thus rocking the ring members c, d , upon their pivot rods b and causing said members to separate and the rings to open, as in Fig. 3.

In assembling the parts I find it advantageous to carry a sheet of flexible material I,—a woven fabric, leather, or the like,—over the backing member D and across the inner faces of the cover-boards F and G, cementing or otherwise securing it to the latter and folding it back under the raised edges of the backing, as seen in Figs. 1, 2 and 3. This, however, is optional, but adds both to the finish and the strength of the structure.

It will be seen that by this construction the impaling hooks or divided rings are given a firm support both when opened and when

closed, and the manipulation of the rings and of the leaves by one hand is rendered possible and easy. This is a great desideratum in binders of this class.

Having thus described my invention, what I claim is:

1. In a binder, the combination of a trough-like support; a series of divided rings pivotally supported therein; a cover; and a rod having pivotal or journal portions seated in the inner ends of the divided-ring sections, and cranked portions adapted to bear respectively against the trough-like support and against the cover and to lower the pivotal or journal portions when said rod is rocked or turned.

2. In combination with a back and cover-boards E, F, G, a concave stiffening member D; a trough-like ring-supporting member A; divided rings B, having their members separately pivoted to opposite edges of said supporting member; cover H; and actuating rod C, pivotally supported in the overlapping inner ends of the ring members, provided with cranked portions e, f , and operating handle g , and serving, when turned, to raise or lower the proximate inner ends of the divided rings.

3. In a binder, the combination of a back and cover-boards; a trough-like holder or support; a cover therefor; two-part rings, the members of which are separately and pivotally mounted in said support; and a locking rod having journal portions mounted in the proximate inner ends of the divided-ring members, and having cranked portions to bear respectively against the ring-support and its cover.

4. In a binder, the combination with a support and divided rings having their members separately and pivotally mounted in said support, and having their proximate inner ends overlapping and provided with notches; a cover for said support; and a rod journaled in the notches of the overlapping inner ends of the ring members, and provided with cranked portions to bear respectively against the ring support and its cover.

5. In a binder, the combination of a trough-like support; a cover therefor; divided rings each having its members separately and pivotally mounted in said support; a rod journaled in the overlapping proximate inner ends of the ring members, and provided with cranked portions to bear respectively upon said support and its cover; and a stop to limit the movement of the cranked portions of the rod.

6. In a binder, the combination with a trough-like support and its cover, of two-part rings the members of which are separately and pivotally mounted in said support; and a rod or rock-shaft journaled in the overlapping inner ends of said ring members, and having a cranked portion which, as the rod is

turned in one direction, bears upon the cover and thereby forces down the journal portions of the rod and with them the inner ends of the divided rings.

5. 7. In a binder, the combination with a trough-like support and its cover, of two-part rings the members of which are separately and pivotally mounted in said support; and a rod or rock-shaft journaled in the overlapping inner ends of said ring members, and having a cranked portion which, as the rod is rotated in one direction, bears upon the

trough-like support and elevates the journal portions of the rod and with them the inner ends of the ring members, thereby throwing 15 apart the outer ends of said members.

In testimony whereof I have signed my name to this specification in the presence of two subscribing witnesses.

JOHN L. McMILLAN.
